Patented Dec. 21, 1920.

INVENTOR.

BY Percy Webster ATTORNEY

UNITED STATES PATENT OFFICE.

ELWOOD A. DILLINGHAM, OF MARYSVILLE, CALIFORNIA.

FARM-GATE.

1,362,929.

Specification of Letters Patent. Patented Dec. 21, 1920.

Application filed October 27, 1919. Serial No. 333,458.

To all whom it may concern:

Be it known that I, ELWOOD A. DILLINGHAM, a citizen of the United States, residing at Marysville, county of Yuba, State of California, have invented certain new and useful Improvements in Farm-Gates; and I do declare the following to be a full, clear, and exact description of the same, reference being had to the accompanying drawings, and 10 to the characters of reference marked thereon, which form a part of this application.

This invention relates to improvements in gates, being particularly intended for use on farms, etc., to be interposed in the lines of 15 fences which bound and subdivide the farm and keep livestock from straying and at the same time to allow a passage over whatever roads, trails, etc., enter the farm from the outside or cross the various subdivisions.

20 The principal object of my invention is to provide a gate whose weight will be counterbalanced and hence easily moved out of the way by movement in a vertical direction, and which when moved to its fullest extent 25 will leave an entirely unobstructed passage therethrough the full width of the road.

Another object is to so construct the gate 30 that it cannot be moved by pressure in a horizontal direction, and consequently will never have a tendency to sag and scrape along the ground as is usual with swing-gates.

A third object is to so construct and proportion the gate that it will remain at any 35 position when the lifting pressure is removed so that relatively wide but low objects such as a flock of sheep, may pass through the gate to the full width of the road without raising it the entire distance.

40 Another object of the invention is to produce a simple and inexpensive device, and yet one which will be exceedingly effective for the purposes for which it is designed.

45 These objects I accomplish by means of such structure and relative arrangement of parts as will fully appear by a perusal of the following specification and claims.

In the drawings similar characters of reference indicate corresponding parts in the 50 several views.

Figure 1 is a side elevation of the gate showing the same closed.

Fig. 2 is a similar view with the gate 55 opened.

Fig. 3 is an enlarged fragmentary top view of the weighted gate frame.

Referring now more particularly to the characters of reference on the drawings, the numeral 1 denotes a rail set to one side of the road transversely thereof and mounted 60 on posts 2 suitably anchored in the ground. Side rails 3 are also secured to the posts a short distance above the ground.

Adapted to straddle the rails and posts is a pair of semicircular disks or plates 4, 65 whose center is above the top of the rails 1, there being a roller 5 at this point between the frames and riding on the rail 1.

The diametrical ends of these disks lie in a vertical plane when the gate is closed, and 70 are adjacent the edges of the road, having top and bottom extensions 6 between each pair of which is secured the ends of the gate frame 7. This frame is preferably made of 75 bent piping, suitably braced by diagonals 8 and covered with wire mesh 9. I do not wish to confine myself however to use this construction of gate.

The gate is of course adapted to extend 80 across the road terminating adjacent a fence post 10 on the other side thereof. A block 11 may be positioned on the ground at this point so that the end of the gate may rest thereon. Guide straps 12 are also mounted to the post and project beyond the end of 85 the gate somewhat so as to aid the same in resisting side pressures thereon.

Each of the disks 4 is provided with a side pocket 13 beyond the pivotal axis of the 90 roller 5, these pockets being filled with lead or a similar weighty substance sufficient to counterbalance the weight of the gate itself.

An arm 14 is pivotally connected to one 95 of the disks 4 at a suitable point near the periphery thereof, preferably on a 90 degree line from the straight end thereof, the other end being pivotally mounted on a bracket 15 secured to the farthest one of the posts 2 just below the rail 1.

The disks 4 extend far enough toward 100 the ground so that very little clearance between the ground and the bottom of the gate is had, the side rails 3 serving as guides for the disks to bear against.

In opening the gate, it is only necessary 105 to exert an easy lifting force on the gate, when it will move upward and at the same time away from the road, the roller 5 riding on the rail 1. The arm 14 being fixed at one end, the plates 4 cannot move horizontally relative to the rail 1, since this arm acts substantially as a pivotal point about 110

- which the disks turn. The only horizontal movement possible therefore is that of the rollers 5 on the rail, thus drawing the gate away from the road as it swings upward.
- 5 A stop pin 16 is fixed to the plate 4 at a desired point thereon, so as to bear on the rail 1 when the gate is in its uppermost position, and so prevent further motion thereof.
- 10 The main fence 17 of the farm extends on one side of the rails 1-3 to a point adjacent the road, since said rail structure is naturally considerably lower than the fence and might permit the escape of livestock 15 thereover.
- From the foregoing description it will be readily seen that I have produced such a device as substantially fulfills the object of the invention as set forth herein.
- 20 While this specification sets forth in detail the present and preferred construction of the device, still in practice such deviations from such detail may be resorted to as do not form a departure from the spirit 25 of the invention, as defined by the appended claims.

Having thus described my invention what I claim as new and useful and desire to secure by Letters Patent is:—

- 30 1. A gate structure comprising a vertical supporting frame rigidly fixed in the ground to one side of a road transversely thereof, a gate member projecting across the road, plates secured to the gate and straddling the frame, a roller between the plates and riding on the top of the frame, the

plates being counterbalanced relative to the gate with the roller as the pivotal point, and means whereby when a lifting force is exerted on the gate the roller will positively move along the top of the rigid frame to move the gate away from the road. 40

2. A gate structure comprising a horizontal rail set rigidly above the ground to one side of a road and transversely thereof, 45 a gate member extending across the road, semicircular plates secured to the gate and straddling the rail, a roller between the plates bearing on the rail, weights on the plates beyond the roller to offset the weight 50 of the gate, and an arm pivotally connected to one of the plates and to the farther end of the rail, whereby when the gate is raised the roller will be caused to move along the rail and draw the gate to one side of the 55 road.

3. A gate structure comprising a horizontal beam supported from the ground extending transversely of a road and to one side thereof, a gate member, a roller fixed 60 to the gate and riding freely on the beam, and forming a pivotal point for the gate, and means connected to the gate and beam whereby the roller will move in a definite and constantly maintained path when the 65 gate is moved vertically.

In testimony whereof I affix my signature in presence of two witnesses.

ELWOOD A. DILLINGHAM.
